Geo. H. Peay of New York, N.Y.
 Letters Patent No. 2137. Dated July 18, 1865.
 Design for Envelopes.

The schedule referred to in these Letters Patent and making part of the same
 To all whom it may concern:

Be it known that I, G. H. Peay, of the County,
 County and State of New York, have invented and improved
 Design for Envelopes; and I do hereby declare that the following is a
 full, clear and exact description thereof, which will enable those
 skilled in the art to make and use the same, reference being had
 to the accompanying drawings forming part of this specification.

The drawing represents an inside elevation of
 this invention.

This invention relates to a design for the interior
 of a folded envelope or more properly speaking for that portion
 of the envelope which is situated under the seal flap when the
 same is folded and the object of the design is to give to my
 envelopes a distinguishing feature, whereby they can be recog-
 nized in the trade at a glance.

In ordinary envelopes the edge of the paper under the
 seal flap presents an appearance such as indicated by a
 dotted line in the drawing. Instead of this I cut the paper
 so that it runs in a slight curve a from both ends towards the
 corners b, and thence it descends rapidly in a straight line c,
 so that when the envelope is folded a triangular recess is
 formed, as shown.

By this form of the edge the object of the de-
 sign in ordinary envelopes, viz., to be able to take hold
 of the letter for the purpose of pulling it from the envelope,
 is attained in a high degree, and the appearance of the
 envelope is as different from that of an ordinary envelope
 that persons acquainted with such articles are enabled to
 distinguish my envelopes at once from those of other man-
 ufacturers.
